(57) **CLAIM**

The ornamental design of a bracket for overhead gate track roller, as shown and described.

DESCRIPTION

FIG. 1 is a perspective view of the bracket for overhead gate track roller in accordance with this invention;
FIG. 2 is a front elevation view of the bracket for overhead gate track roller of the present invention;
FIG. 3 is a side elevation view of bracket for overhead gate track roller of the present invention; the opposite side being a mirror image thereof; and,
FIG. 4 is a top plan view thereof. The bottom and rear views are unornamented.
